(57) **CLAIM**

The ornamental design for a reconfigurable rocking chair, as shown and described.

DESCRIPTION

FIG. 1 is a perspective view of a reconfigurable rocking chair showing my new design, the reconfigurable rocking chair being shown in a first configuration.

FIG. 2 is a left side elevation view of the reconfigurable rocking chair shown in FIG. 1;

FIG. 3 is a right side elevation view of the reconfigurable rocking chair shown in FIG. 1;

FIG. 4 is a front elevation view of the reconfigurable rocking chair shown in FIG. 1;

FIG. 5 is a back elevation view of the reconfigurable rocking chair shown in FIG. 1;

FIG. 6 is a top plan view of the reconfigurable rocking chair shown in FIG. 1;

FIG. 7 is a bottom plan view of the reconfigurable rocking chair shown in FIG. 1;

FIG. 8 is a perspective view of a reconfigurable rocking chair showing my new design, the reconfigurable rocking chair being shown in a second configuration.

FIG. 9 is a left side elevation view of the reconfigurable rocking chair shown in FIG. 8;

FIG. 10 is a right side elevation view of the reconfigurable rocking chair shown in FIG. 8;

FIG. 11 is a front elevation view of the reconfigurable rocking chair shown in FIG. 8;

FIG. 12 is a back elevation view of the reconfigurable rocking chair shown in FIG. 8;

FIG. 13 is a top plan view of the reconfigurable rocking chair shown in FIG. 8; and,

FIG. 14 is a bottom plan view of the reconfigurable rocking chair shown in FIG. 8.

1 Claim, 12 Drawing Sheets
